CLAIM

The ornamental design for a combined toothbrush and case, as shown and described.

DESCRIPTION

FIG. 1 is a side elevational view, with the toothbrush in stored position;

FIG. 2 is a top plan view thereof;

FIG. 3 is a bottom plan view thereof;

FIG. 4 is an end elevational view thereof;

FIG. 5 is an opposite end elevation view thereof;

FIG. 6 is a side elevational view showing the toothbrush and case in a position of use;

FIG. 7 is a top plan view thereof;

FIG. 8 is a bottom plan view thereof; and,

FIG. 9 is an end elevational view thereof, corresponding to the end elevational view of FIG. 4 but with the toothbrush in its position of use.

Fig. 2.

Fig. 1.

Fig. 3.

Fig. 4.
